UNITED STATES PATENT OFFICE

JOSEPH J. SCHMERLER, OF BRONX, NEW YORK

COMBINED OPENER AND CLOSURE FOR PAPER MILK CONTAINERS

Application filed May 28, 1931. Serial No. 540,712.

This invention relates to the combined opener and closure for paper milk containers disclosed in my U. S. Letters Patent, No. 1,785,599 granted December 16, 1930. The 5 opener and closure comprises, as disclosed in said patent, a pointed blade for removing the upper portion of a container, a channel member adapted to close a part of the opening formed by the removal of such portion 10 of the container, the blade being carried by one end of the channel member to effect the application of said member to the container during the removal of the upper portion of the container, and a pouring spout carried by 15 the other end of the channel member and communicating with the remaining portion of the opening formed by the removal of the upper portion of the container.

The present invention has for one of its 20 objects to improve and simplify the general construction of the opener and closure to the end that its cost of manufacture may be materially reduced, to the end that it may be more readily used to effect the removal of 25 the upper portion of a container, and to the end that it may be more firmly secured to the container.

To attain the foregoing and other objects, the nature of which will appear as the description proceeds, the invention comprehends omitting the spout of the opener and closure and substitute therefor means which during the application of the opener and closure to a container, will form a corner of 35 the open end of the container into a pouring opening.

The invention further comprehends the provision of an opener and closure of the character stated wherein the pouring opening forming means shall consist of a spreader carried by one end portion of a channel member and adapted, during the application 40 of the opener and closure to the container, to space the side walls of the container near a corner of the latter, and a former terminally carried by the channel member outwardly of the spreader and adapted to limit the spacing of the side walls of the container, 45 the spreader and former cooperating to

maintain the spaced walls of the container in pouring opening forming relation.

The invention further comprehends the provision of an opener and closure of the character stated wherein the former shall be provided with means adapted to engage the walls of the container to maintain the 55 opener and closure on the container against accidental displacement therefrom.

The invention further comprehends the provision of an opener and closure of the character stated wherein the blade shall be provided with an inclined cutting edge to the end that it may more readily cut off the upper portion of the container.

The invention is hereinafter more fully described and claimed, and illustrated in the accompanying drawing, wherein:

Figure 1 is a view in side elevation illustrating the opener and closure applied to a 70 paper milk container, the dotted lines indicating that portion of the container removed during the application of the opener and closure.

Figure 2 is a top plan view of the opener 75 and closure.

Figure 3 is a sectional view taken on a vertical plane extending longitudinally and centrally through the container and the 80 opener and closure.

Figure 4 is a sectional view taken on the vertical plane indicated by the line 4-4 of Figure 3.

Figure 5 is a sectional view taken on the vertical plane indicated by the line 5-5 of 85 Figure 3.

Figure 6 is a sectional view taken on the horizontal plane indicated by the line 6-6 of Figure 3, and

Figure 7 is a sectional view taken on the horizontal plane indicated by the line 7-7 of 90 Figure 3.

Referring in detail to the drawing, 1 designates a paper container for milk, and 2 the opener and closure for the container. After the milk has been placed therein, the container 95 1 is closed by a metallic sealing strip 3 which clamps together the upper end portions of the walls of the container. As the container 1 and its sealing strip 3 are of well-known con-

struction, a further description thereof is deemed unnecessary.

The opener and closure comprises a channel member 5 which is made from light sheet metal. The top wall 5a of the channel member 5 has one end thereof arranged diagonally and sharpened to provide a blade 6, and the side walls 5b of the channel member are extended longitudinally beyond the blade 6 to provide guides 7 which have their free end portions curved laterally outward. A spreader 8 extends longitudinally from the other end of the top wall 5a, the spreader being of V-form in cross section, and gradually increasing in width and depth outwardly from its inner to its outer end. A former 9 which is associated with the channel member 5 and the spreader 8 consists of side walls 9a and end walls 9b. The side walls 9a of the former 9 extend in outwardly divergent relation from the side walls 5b of the channel member 5 and extend downwardly from the side edges of the spreader 8.

The spreader 8 is located within the former 9, and the outer edge of the spreader is curved and cooperates with the curved end wall 9b of the former to provide an opening 10. The end wall 9b of the former 9 is of greater width than the side walls 5b of the channel member 5 and it extends downwardly from a plane coincident with the upper surface of the top wall 5a of the channel member. All parts of the device are formed integrally with each other, and the device may be readily manufactured from light sheet metal.

In practice, one edge of the container 1 is introduced between the guards 7 until the blade 6 engages said edge at a point close to the lower edge of the sealing strip 3 of the container. The device is then manipulated to carry the blade 6 to and beyond the opposite edge of the container 1 with the result that the sealed upper portion of the container is removed. During the severing of the sealed upper portion of the container 1, the channel member 5 is applied to the container in such manner as to close a portion of the opening being formed, the guides 7 directing the walls for the container into the channel member during the application of the latter. During the application of the channel member 5 to the container 1, the spreader 8 moves in between the side walls 4 of the container and spreads such walls into contact with the walls of the former 9, this being possible due to the gradual increase in width and depth of the spreader and the divergent relation of the side walls 9a of the former. The spreading of the walls of the container 1 into the former 9 provides the container at an upper corner thereof with a pouring opening which registers with the opening 10 of the device, and the contents of the container will discharge readily through this opening when the container is tilted.

The wall 9b of the former 9 is provided at its upper edge with a downwardly directed flange 9c which is located within the former and which receives the upper edges of portions of those container walls located within the former. The flange 9c, the spreader 8, and a prong 11 carried by the wall 9b of the former 9 and engaging the container 1, hold those portions of the container walls located within the former in close contact with the walls of the former, with the result that such wall portions are maintained in opening forming relation. The distance between the side walls 5b of the channel member 5 is less than the combined thickness of the container walls 4 in order to cause the snug application of the device to the container, the device being held against accidental displacement from the container by the prong 11, by projections 12 struck up from the walls 5b adjacent the guide 7 and engaging the walls of the container, and by the flange 9c.

From the foregoing description, taken in connection with the accompanying drawing, it should be apparent that through the medium of the device the sealed upper end of a paper milk container may be easily and quickly removed, that the device is applied to the milk container during the removal of its sealed upper end, that after its application the device covers the greater portion of the opening provided by the removal of the sealed upper end of the container, and the remaining portion of the open end of the container is in registration with the pouring opening of the device, and that the walls of the remaining portion of the open end of the container are maintained in spaced relation by the spreader and former in order to permit the contents of the container to be easily poured through the opening of the device.

While I have described the principle of the invention, together with the structure which I now consider the preferred embodiment thereof, it is to be understood that the structure shown is merely illustrative and that such changes may be made, when desired, as fall within the scope of the invention as claimed.

What is claimed is:—

1. A device of the character set forth, comprising a blade adapted to remove the upper end portion of a closed container, a closure for a part of the opening formed by the removal of said container portion, the closure carrying the blade and adapted to be applied to the container during the removal of said portion of the latter, a former carried by the closure and provided with an opening adapted to register with the remaining portion of said first opening after the application of the closure, and a spreader carried by the closure and former and adapted during the application of such parts to spread the walls of said remaining portion of said opening.

2. A device of the character set forth, comprising a blade adapted to remove the upper end portion of a closed container, a closure for a part of the opening formed by the removal of said container portion, the closure carrying the blade and adapted to be applied to the container during the removal of said portion of the latter, a former carried by the closure and provided with an opening adapted to register with the remaining portion of said first opening after the application of the closure, a spreader carried by the closure and former and adapted during the application of such parts to spread the walls of said remaining portion of said opening, and elements carried by the closure and former and engaging the container to hold the device against accidental displacement from the container. 70
- 10 3. A device of the character set forth, comprising a channel member having its top wall at one end of the device inclined from one to the other of its side walls to provide a blade, a former at the other end of the device and gradually increasing in width in an outward direction, and a spreader at said last end of the device within the former. 80
- 15 4. A device of the character set forth, comprising a channel member having its top wall at one end of the device inclined from one to the other of its side walls to provide a blade, a former at the other end of the device and having side walls and a curved end wall, the side walls converging inwardly and connected to the side walls of the channel member, and a spreader located within the former and connected to the side wall of the latter and to the top wall of the channel member. 85
- 20 5. A device of the character set forth, comprising a channel member having its top wall at one end of the device inclined from one to the other of its side walls to provide a blade, a former at the other end of the device and having side walls and a curved end wall, the side walls converging inwardly and connected to the side walls of the channel member, and a spreader located within the former and connected to the side wall of the latter and to the top wall of the channel member, the spreader being of V-form in cross section and gradually increasing in width and depth in the direction of the end wall of the former, and the outer edge of the spreader being curved and cooperating with said end wall to provide a pouring opening. 90
- 25 6. A device of the character set forth, comprising a channel member having its top wall at one end of the device inclined from one to the other of its side walls to provide a blade, a former at the other end of the device and having side walls and a curved end wall, the side walls converging inwardly and connected to the side walls of the channel member, a spreader located within the former and connected to the side wall of the latter and to the top wall of the channel member. 95
- 30 7. A device of the character set forth, comprising a blade adapted to remove the upper end portion of a closed container, a closure for a part of the opening formed by the removal of said container portion, the closure carrying the blade and adapted to be applied to the container during the removal of said portion of the latter, a former carried by the closure and provided with an opening adapted to register with the remaining portion of said first opening after the application of the closure, a spreader carried by the closure and former and adapted during the application of such parts to spread the walls of said remaining portion of said opening, and a flange carried by the former and adapted to engage over the upper edges of the walls of said remaining portion of said opening. 100
- 35 8. A device of the character set forth, comprising a blade adapted to remove the upper end portion of a closed container, a closure for a part of the opening formed by the removal of said container portion, the closure carrying the blade and adapted to be applied to the container during the removal of said portion of the latter, a former carried by the closure and provided with an opening adapted to register with the remaining portion of said first opening after the application of the closure, a spreader carried by the closure and former and adapted during the application of such parts to spread the walls of said remaining portion of said opening, a flange carried by the former and adapted to engage over the upper edges of the walls of said remaining portion of said opening, and a prong carried by the former and engaging said walls below said flange. 105
- 40 In testimony whereof I hereunto affix my signature.
